(57) **CLAIM**

The ornamental design for an inflator, as shown and
described.

DESCRIPTION

FIG. 1 is a perspective view of the inflator, according to the
invention;

FIG. 2 is a front view of the inflator shown in FIG. 1;

FIG. 3 is a rear view of the inflator shown in FIG. 1;

FIG. 4 is a side view of the inflator shown in FIG. 1;

FIG. 5 is a side view, opposite the side view shown in FIG.
4, of the inflator shown in FIG. 1;

FIG. 6 is a top view of the inflator shown in FIG. 1; and,

FIG. 7 is a bottom view of the inflator shown in FIG. 1.

The broken lines depict portions of the inflator that form no
part of the claimed design.

1 Claim, 7 Drawing Sheets
